[57] CLAIM

The ornamental design for a front face of a vehicle wheel, as shown and described.

DESCRIPTION

FIG. 1 is a front elevational view of the front face of a vehicle wheel embodying my novel design;

FIG. 2 is a side perspective view thereof; and

FIG. 3 is a front perspective view thereof.

The broken line showing of a tire in the drawing is for illustrative purposes only and forms no part of the claimed design.

FIG. 1

FIG. 2

FIG. 3
